UNITED STATES PATENT OFFICE.

FRANK H. MOONEY, OF CHICAGO, ILLINOIS.

GOLF BAG.

Application filed January 15, 1927. Serial No. 161,271.

My invention relates to improvements in golf bags and has for one object to provide a new and improved form of golf bag wherein in automatic means insure that the bag when released by the user will remain in upright position. Another object is to provide an automatic standard or support for the bag which goes into operation when the operator lets go of the handle or strap and holds the body of the bag and which automatically is withdrawn into the bag when the bag is lifted by the handle or strap. Other objects will appear from time to time throughout the specification and claims.

My invention is illustrated more or less diagrammatically in the accompanying drawings, wherein—

Figure 1 is a side elevation;

Figure 2 is a longitudinal section;

Figure 3 is a cross section along the line 20 3—3 of Figure 2;

Figure 4 is a top plan view;

Figure 5 is a longitudinal section through a modified form;

Figure 6 is a top plan view of the form shown in Figure 5.

Like parts are indicated by like characters throughout the specification and drawings.

A is a golf bag of fabric, leather or other suitable material. It is closed at the bottom by a relatively rigid cap A¹ of metal, leather, fiber or other suitable material which may be riveted or otherwise suitably fastened to the lower extremity of the bag body. A² is a rim at the upper open end of the bag. A³ is a bag shoulder strap attached at one end to the bag intermediate its ends and to the upper end. A⁴ is a handle projecting from the side of the bag.

The bag is held in shape by a framework which in this case differs somewhat from the framework ordinarily used in connection with golf bags and the like. This framework comprises a plurality of upwardly extending arms B which may be integral or if not integral suitably attached to the bottom A¹. These arms upwardly converge and join in a sleeve B¹ from which extends upwardly a central hollow tube B². Threaded on this tube is a T, B³, the branch of the T, B⁴, extending diagonally upward to and terminating at the outer wall of the bag where it is attached to the wall by the flange B⁵. B⁶ is a central hollow shaft extending from the other branch of the T upwardly to the top of the bag where it carries a sleeve B⁷ which

in turn supports radial arms B⁸ integral with or otherwise suitably attached to the rim A².

Slidably mounted in the tube B² is a reciprocating shaft C. This shaft extends out beyond the sleeve B¹ into the space enclosed by the arms B where it is mounted on a reciprocating or slidable hub C¹, there being a coil spring C² interposed between the hub C¹ and the sleeve B¹. C³ C⁴ are a plurality of supporting arms each pivoted on its inner end to the hub C¹ and each slidably in guideways C⁴ in the base A¹. These arms C³ have ground contacting foot elements C⁵ and when the hub C¹ is in the downward position held there by the force of gravity or by the coil spring C² these arms C³ are projected outwardly from the bag and form a broad ground engaging support to hold the bag upright and prevent its tipping over.

The upper end of the rod C terminates in a ring D. A chain D¹ extends from this ring upwardly through the tube B⁴ and supports the lower end of the handle A⁴. A chain D² extends from the ring D up through the tube B⁶ out from the center of the bag and supports the upper end of the shoulder strap A³. D³ is a hook or latch on the rim A² so positioned that if the operator so desires he can engage that hook with the end of the chain D² and thereby hold the spring C² in compressed position and the hub C¹ in the upper position so that the bag can be handled and manipulated with the standard retracted into the bag just as if the bag were the ordinary type.

In the modified form shown in Figure 5, there is substituted for the tube B² an inclined tube E bent at E¹ so that the hub, tube or hollow rod element E² terminates not at the center of the bag at the top but at the side adjacent the handle, the result of this being that the bag instead of being supported by a strap at the center of the bag is supported at the side.

It will be understood that the golf clubs can be inserted into the bag in the space between the rim and the central sleeve and will be grouped around the hollow tube or backbone of the bag and will not in any way interfere with the operation of the device because the lower ends of the handles of the clubs will be held out of contact with the hub or rim elements by their engagement with the members B.

In the modified form shown in Figure 5, the hollow shaft is dispensed with. The bag has

the ordinary frame made up of side ribs G G extending up from a base G¹ to an upper ring G². In this case the upwardly converging guard members G³ extend up from the 5 bottom of the bag and support the upper end of a fixed pin G⁴ on which slides a hub G⁵. Ground contacting arms G⁶ are pivoted to the hub G⁵ and a coil spring is interposed between the hub G⁵ and the upper end of the 10 pin so that the operator is in the same position as in the preferred form except that the hub slides on the pin instead of traveling with it. The chain G⁷ extends from the hub G⁵ up to the handle G and a similar chain 15 up to the shoulder strap G⁸ so that the operation is the same.

The use and operation of my invention are as follows:

My golf bag is primarily intended for use 20 by players who do not have caddies to carry their bags and avoids the necessity of laying the bag down and stooping over to select clubs or stooping over to pick the bag up.

The operator always carries the bag 25 through the strap over his shoulder or by holding the handle of the bag. In either case, the strap or the handle tends to move toward the top of the bag and this exerts the tension on the connection which is preferably a 30 chain, strap or rod inside the body of the bag between the handle and the shoulder strap at one end and the automatic stand mechanism at the other. The tension of this connection compresses the coil spring or overcomes the 35 force of gravity as the case may be and withdraws the stand, locks back into the body of the bag so that when the bag is being carried it looks and operates just as an ordinary bag and this situation prevails just as long as the 40 operator continues to hold it by the handle or by the strap. When the operator is about to put the bag down, he holds it by the body of the bag, the tension on the connecting mechanism is released and the weight of gravity 45 or the weight of gravity plus the coil spring if that is used, thrusts the supporting arms out from the bag to form a stand which insures that the bag when stood on the ground in upright position will still remain.

If on the other hand the operator wants the stand to be permanently out of operation he merely throws the latch which engages the chain on the hook so that the stand mechanism is held in the inoperative position independent of the manipulation of the handle or strap and this position prevails until the chain is released.

I claim:

1. The combination with a golf bag of a ground engaging support at the lower end thereof, a handle and a shoulder strap, each associated with the upper end of the bag and connections between them and the support 65 whereby tension on either the handle or the

strap will automatically move the support into an inoperative position.

2. The combination with a golf bag of a plurality of ground engaging arms at the bottom thereof, a handle and a shoulder strap 70 and connections between them and the arms whereby tension on either the handle or the strap will move the ground engaging arms to an inoperative position.

3. The combination with a golf bag of a plurality of ground engaging arms at the bottom thereof, a handle and a shoulder strap 75 and connections between them and the arms whereby tension on either the handle or the strap will retract the ground engaging arms 80 into the bag.

4. The combination of a golf bag of a frame comprising a central hollow shaft, a plurality of rigid arms associated with the lower end thereof, guideways carried thereby, ground contacting members slidably in said guideways, a central hub upon which their inner ends are pivoted, a rod slidably in the tube, supporting the hub at its lower end, supporting means associated with the upper 90 end of the bag and a connection between said means and the rod whereby when the supporting means are used the rod will be moved upwardly to retract the ground contacting members.

5. The combination with a golf bag of a ground engaging support at the lower end thereof, a carrying means associated with the upper end of the bag, a tensional connection between said carrying means and said support adapted normally to withdraw said support into inoperative position, when tension is exerted upon said carrying means, and means for moving said support into operative position when the tension upon said carrying means is released.

6. The combination with a golf bag of a ground engaging support at the lower end thereof, a carrying means associated with the upper end of the bag, a tensional connection 100 between said carrying means and said support adapted normally to withdraw said support into inoperative position, when tension is exerted upon said carrying means, and means for moving said support into operative 105 position when the tension upon said carrying means is released, said support being substantially completely housed within said bag when in inoperative position.

7. The combination with a golf bag of a ground engaging support at the lower end thereof, a carrying means associated with the upper end of the bag, a tensional connection between said carrying means and said support adapted normally to withdraw said support 120 into inoperative position when tension is exerted upon said carrying means, said support including a plurality of radial elements, a central member to which said elements are pivoted and means for moving said support 125 130

into operative position when the tension upon said carrying means is released, including yielding means for thrusting said central member downwardly toward the bag bottom.

8. The combination with a golf bag of a plurality of ground engaging supporting arms positioned at the lower end thereof, carrying means associated with the upper end 10 of said bag and a connection between the carrying means and the arms whereby the arms are automatically retracted into the body of the bag when tension is exerted upon said carrying means, and positive yielding 15 means adapted to thrust the supporting arms into ground engaging, bag supporting position upon release of said tension.

9. The combination with a golf bag of a plurality of ground engaging supporting 20 arms positioned at the lower end thereof, carrying means associated with the upper end of said bag and a connection between the carrying means and the arms whereby the arms are automatically retracted into the 25 body of the bag for substantially their entire length when tension is exerted upon said

carrying means, and means for thrusting said arms outwardly from the bag when tension upon said carrying means is released including a yielding member operable to thrust said 30 arms outwardly from the bag.

10. The combination of a golf bag of a frame comprising a central hollow shaft, a plurality of rigid arms associated with the lower end thereof, guideways carried thereby, ground contacting members slidably in said guideways, a central hub upon which their inner ends are pivoted, a rod slidable in the tube, supporting the hub at its lower end, supporting means associated with the 35 upper end of the bag and a connection between said means and the rod whereby when the supporting means are used the rod will be moved upwardly to retract the ground contacting members, and locking means whereby 40 the rod may be locked in the upper position independent of the bag supporting means.

Signed at Chicago, county of Cook and State of Illinois, this 28th day of December, 1926.

FRANK H. MOONEY.
